CLAIM

The ornamental design for a hair clip, as shown and described.

DESCRIPTION

FIG. 1 is a perspective view of a hair clip;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines depicting portions of the hair clip do not form part of the claimed design.

The contour lines shown in each view of the drawings are lines representing the surfaces of the solid body and are not surface pattern.
